United States Patent Office

Des. 216,331
Patented Dec. 16, 1969

216,331

STRINGED MUSICAL INSTRUMENT

Walter J. Pelensky, 19C Manheim Gardens,
Philadelphia, Pa. 19144

Filed Mar. 28, 1968, Ser. No. 11,179

Term of patent 14 years

Int. Cl. D17—03

U.S. Cl. D56—1

Fig. 1

Fig. 3

Fig. 2

Fig. 4

FIG. 1 is a perspective view of a stringed musical instrument, showing my new design;

FIG. 2 is an elevational or face view;

FIG. 3 is a left side elevational view;

FIG. 4 is a right side elevational view.

Portions of the drawings are shaded to indicate contrast.

I claim:

The ornamental design for a stringed musical instrument, as shown and described.
